UNITED STATES PATENT OFFICE.

JOSEPH M. NELSON, TODD C. MORITZ, AND WILLIAM DILLEY, OF DENVER, COLORADO.

DRILLING MACHINE.

Application filed February 23, 1923. Serial No. 621,118.

To all whom it may concern:

Be it known that we, JOSEPH M. NELSON, TODD C. MORITZ, and WILLIAM DILLEY, citizens of the United States, residing at Denver, in the county of Denver and State of Colorado, have invented certain new and useful Improvements in Drilling Machines, of which the following is a specification, reference being had to the accompanying drawings.

This invention relates to drilling machines, such as rock drilling machines and the like, and particularly to a drilling machine wherein the drill is reciprocated by a power operated cam or equivalent element.

One of the objects of the invention is to provide a drill of this character which is adapted to be operated either by hand or by a motor, such as an electric motor.

A further object is to provide means whereby the speed of rotation of said cam shall control the stroke of the drill.

A still further object is to provide simple but very effective means whereby the hammer which is contained within the casing of the drill may be projected with force against the anvil which operates against the drill or is connected thereto, and in connection therewith improved means whereby the chuck within which the drill is mounted may be rotated during the operation of the drill.

Still a further object is to provide levers for reciprocating the hammer, and a power operated cam of peculiar form which reciprocates these levers to cause the reciprocation of the hammer.

Another object is to provide means whereby the casing containing the drill and the operating mechanism therefor may be positively fed forward step by step and whereby in case the drill cannot feed forward as fast as the feeding mechanism operates the difference is compensated for.

Still another object in this connection is to provide means whereby the feeding dog and the holding dog may be raised from the toothed feed bar with which they operate so as to permit the drill and its casing to be removed away from the work whenever desired.

Other objects will appear in the course of the following description.

Our invention is illustrated in the accompanying drawings, wherein:

Figure 1 is a longitudinal sectional view 55 of a rock drill constructed in accordance with our invention, showing the base upon which the drill is mounted and part of the drill column;

Figure 2 is a section on the line 2—2 of 60 Figure 1;

Figure 3 is a section on the line 3—3 of Figure 1;

Figure 4 is a section on the line 4—4 of 65 Figure 1;

Figure 5 is a fragmentary vertical section of the rear end of the drill casing, showing the means for feeding the drill;

Figure 6 is an enlarged fragmentary section showing the stellate wheel 32 as it acts 70 to move the hammer forward;

Figure 7 is a fragmentary longitudinal section showing the means for rotating the drill chuck;

Figure 8 is a section on the line 8—8 of 75 Figure 1;

Figure 9 is a fragmentary elevation of the drill.

Referring to these drawings, 10 designates the casing of the drill. This casing is 80 relatively narrow but rearward of its forward end is downwardly enlarged. The upper portion of the forward end of the casing is cylindrical in form to contain the drill chuck for the drill 11. This drill chuck is 85 composed of two tubular sections 12 and 13, the section 12 being rectangular in cross section and having a cylindrical extension 14 which is screw-threaded upon its inner and outer faces at 15. The section 13 is cylindrical in cross section and is disposed within the cylindrical bore of the section 12 so as to rotate therein. This section 13 is formed at spaced points with circumferentially extending grooves 16. The rear end 95 of this section 13 has an exteriorly screw-threaded hub 17.

Passing through the section 12 are bolt holes for the passage of bolts 18 which engage in the circumferential groove 16 and which hold the section 13 within the section 12 but permit the rotation of the section 13. The section 13 is formed with a many-sided bore or socket 19 within which the drill 11

is disposed. This drill 11 has a many-sided shank fitting this many-sided bore or socket, and preferably the drill from the point rearward is made of flanged steel twisted into the shape of an auger whereby to carry the dust out of the drill hole as the drill is rotated.

It will be seen that a rotation of the section 13 will act to rotate the drill, while at the same time the drill is free to move longitudinally within the section 13 of the chuck. The section 12 of the chuck forms a carrier for the section 13 which prevents any longitudinal movement of the section but permits rotative movement thereof. An exteriorly threaded, dust protecting nut 20 which has a circular bore is engaged with the interior screw-threads of the screw-threaded extension 14 of the section 12, and a locking nut 21 which is interiorly screw-threaded is engaged with the outer threads of the extension 14. Mounted upon the screw-threaded hub 17 is a ratchet wheel 22 whose manner of operation will be later described. This ratchet wheel has a central bore, and operating within the cylindrical wall 23 which forms part of the casing 17 is an anvil 24 having a shank 25 which passes loosely through the opening in the ratchet wheel and bears against the rear end of the shank 11.

Disposed in axial alignment with the axis of the anvil 24 and of the drill 11 and operating in a suitable barrel 26 is the hammer 27 which is in the form of a longitudinally extended bar, and disposed within the rear end of the barrel 26 is a coiled compression spring 28 which forms a cushion or bumper against which the hammer impinges upon its rearward movement. The head of the anvil 24 also bears against a coiled compression spring 29, in turn bearing against a shoulder 30 of the barrel within which the anvil operates.

Passing through the sides of the casing 10 and mounted in suitable bearings therein is a shaft 31, and mounted upon this shaft for rotation therewith and disposed approximately in the same plane as the hammer 27 is a star cam wheel 32, shown as a wheel having six equi-disposed angular teeth rounded at their extremities. Pivotally mounted forward of this star wheel and within the casing is a rocker arm 33 which is mounted upon a pivot pin 34, this rocker arm having a projection 35 which extends through a slit in the wall of the barrel 26 and extends into a recess 36 in the hammer. The lower extremity of the rocker arm is provided with a downwardly extending arm or tooth 37 which extends into a longitudinally reciprocating counter balance 38. The rear face of this rocker arm is cut away at 39 and the teeth of points of the star wheel cam 32 move through

this recess or space 39. Rearward of the star wheel cam 32 is disposed a second rocker arm 40 which is of like form to the rocker arm 33 and is provided with the upwardly extending tooth, lug or arm 41 which engages in a recess 42 in the hammer 27, while the lower extremity of the rocker arm is formed with a downwardly projecting tooth or lug 43 which engages in the recess 44 in the confronting face of the counterbalance 38. This rocker arm 40 is loose upon a shaft 45 equivalent to the pivot pin or shaft 34.

The shaft 31 upon which the cam 32 is mounted carries a gear wheel 46 with which an idler gear wheel 47 engages, this idler gear wheel in turn meshing with a relatively large gear wheel 48 mounted upon the shaft 45 and adapted to be driven by the rotation thereof. This shaft 45 is adapted to be driven by a crank or by a motor, and it will be seen that its rotation in a clockwise direction will give a clockwise rotation to the shaft 31 and the star wheel 32. As the star wheel rotates, one of its teeth will engage against the rearwardly projecting portion 33^a of the rocker arm above the recess 39 and will force the adjacent end of this rocker arm 33 forward, while the opposite end 37 will be forced rearward. Thus the hammer will be projected forward and strike against the anvil 24, thus driving the drill forward. At the same time that one point or tooth of the star wheel 32 is engaging against the abutment 33^a to oscillate the rocker 33 in one direction, the diagonally opposite tooth of the star wheel is engaging with the lower face of the rocker 40 so that the tooth 41 is forced forward at the same time that the tooth 35 is forced forward, while the teeth 37 and 43 are forced rearward.

Thus while the hammer 27 is being projected forward, the counterbalance 38 is being projected rearward. This counterbalance 38 is mounted in a suitable barrel 49 which is open along that side confronting the rocker arms and the star wheel, and in the ends of this barrel are disposed the compression springs 50 against which the counter wheel 38 impinges. These cushioning springs 50 will cause the counterbalance to spring back to its longitudinal position as the full stroke has been made which will carry the hammer back to its original position and, in fact, beyond this position where the hammer will strike the cushioning spring 28 and again move forward to its original position.

As the hammer is driven forward it strikes the anvil 24, the shank of which strikes the drill and drives the drill forward, and upon a reverse motion of the rocker arm 33 the chuck on which the

drill is mounted is given a slight rotation. This is accomplished as follows: As illustrated in Figure 4, the ratchet wheel 22 has its teeth engaged by a longitudinally reciprocatable pawl 51 whose extremity is formed with a tooth or is hooked so as to engage with the ratchet teeth of the wheel 22. The extremity of this reciprocatable pawl 51 (see Fig. 7) is engaged by a bell crank lever 52 pivotally supported at 53 within the casing and whose long arm is connected by a link 54 to the rocker 33 at a point to one side of its pivot 34 and preferably between its pivot 34 and the hammer 27. Therefore, as the toothed end 35 of the rocker 33 moves forward, the pawl 51 will be given a movement upward in Figure 4 so that it will slide over the teeth of the ratchet wheel 22. Upon a reverse movement of the rocker 33, however, the pawl will be pulled downward in Figure 4 and its teeth engaging the ratchet wheel will cause the ratchet wheel to turn a distance of one tooth, thus turning the chuck 13 and, of course, turning the drill through a small fraction of a circle.

In order to prevent a backward movement of the ratchet wheel, the chuck and the drill, we provide a dog 55 which is pivoted at 56 upon a bracket 57 and which rides against the teeth of the ratchet wheel and which is held in engagement with these teeth by means of a spring 58 illustrated as connected with the pawl 51. This spring 58, therefore, holds the pawl 51 in position against the ratchet teeth but permits the pawl 51 to ride over the ratchet teeth in its reverse movement and at the same time holds the pawl 52 to the ratchet teeth, preventing a reverse movement of the ratchet wheel but riding over the teeth upon a forward movement of the ratchet wheel. This bracket 57 is, of course, attached to the casing wall.

For the purpose of feeding the casing toward the breast of the work, we provide a feeding dog 59 which projects through a slot 60 in the casing and which is engageable with a ratchet bar 61 mounted as will be hereafter stated. This pawl 59 is pivoted to a reciprocating eccentric rod 62, which at its upper end has a sleeve 63 which, of course, fits the eccentric 64, this eccentric being preferably mounted upon the shaft 31. The pawl 59 is pivoted to the eccentric rod 62 by a pivot pin 65 and the pawl extends beyond this pivot pin or has a rearward extension or tail which coacts with a stop lug 66 on the eccentric rod. An arcuate spring 67 which is attached to the wall of the casing has its free curved end bearing against the edge face of the tail 68 of pawl 59 and forces this pawl normally against this stud 66. It will be seen that with this

construction as the eccentric 64 is rotated, 65 a reciprocating movement will be given to the rod 62 and the pawl operating against the fixed rack 61 will shift the casing 17 and, therefore, the drill longitudinally step by step toward the work. A 70 holding dog 69 is mounted upon a pin 70 on a bracket 71 attached to the inside of the casing 10, the dog projecting through a slot in the casing and engaging the teeth 61 so as to hold the casing in its advanced position each time it is fed forward by the feeding dog 59.

This dog 69 is urged against the toothed bar by a spring 72 and both dogs 59 and 69 may be simultaneously raised out of engagement with the toothed bar to permit the machine to move back by a lever 73 having a longitudinal bar 74 attached thereto provided with studs 75 which bear against the forward edges of the dogs 59 and 69, this lever having an operating handle on the exterior of the case whereby it may be shifted to raise both dogs from the rack bar or permit both dogs to be shifted into engagement with the rack bar by the springs 67 90 and 72 respectively.

The rack bar 61 is disposed against the upper face of a recessed base plate 76, as illustrated in Figure 2, which is attached to a conical base 77, which is in turn held to 95 the arm of a drilling column 78 by means of clamps 79 mounted on bolts 80 extending into the column. The inner face of the base plate 76 is recessed at 81 and bridging this recess is a plate 82 which forms part of the casing and projects beyond the casing and is held in place in sliding engagement with the base plate 18 by means of the overhanging guide strips 83 which engage over the projecting portions of the plate 82 and are 100 held in place by screws 84.

As before stated, the revolution of the eccentric 64 reciprocates the dog 59, and when this dog 59 engages with the teeth on bar 61 the whole machine will move forward toward the breast of the work far enough to permit the holding dog 69 to engage one cog forward from its former position. In case, however, that the drill bit is not cutting as fast as this feeding mechanism is capable of moving the machine forward so that the dog 69 will not advance a notch at each stroke of the dog 59, the hinged joint formed by pivoting the dog 59 upon the eccentric rod 62 will compensate for this difference until the dog 69 can catch the next forward notch. The spring 67 bearing against the tail of the dog 59 prevents this spring joint from operating too freely.

This drill may be operated either by hand or by a motor as, for instance, an electric motor. While no electric motor is illus-

trated, it is obvious that this might be accomplished by connecting the electric motor to the shaft 31 through worm gears or any other suitable gears. In case the 5 drill is driven either by hand or electric power, the driving would be geared in such a ratio as would deliver from 400 to 500 blows per minute against the drilling bit. As illustrated, the drive is geared in the 10 ratio of 13 to 1, that is the hammer strikes 13 blows to each complete revolution of the crank handle. The actual gear ratio, however, is not quite so great because as the hammer strikes once for each point of the 15 star cam as the star cam revolves there are six blows of the hammer to each revolution of the star cam.

Because of the fact that the weight of the 20 hammer blow is dependent upon its velocity, it is possible to strike a heavier or a lighter blow by increasing or decreasing the R. P. M. of the shaft 31. To strike a normal blow the shaft 31 should make approximately 40 R. P. M. This can be changed, 25 however, by changing the ratio of gears 46, 47 and 48.

While we have illustrated a six-pointed cam, a three-pointed cam may also be used, and it is obvious that this cam might be 30 modified in some respects without departing from the spirit of the invention. We do not wish to be limited to any power operated means for driving the cam, nor to the details of construction, as these may be 35 changed in many ways without departing from the spirit of the invention as defined in the appended claims.

We claim:

1. In a rock drill, a reciprocatable drill proper, a reciprocatable hammer separate from but adapted to impinge upon the drill, a stellate power driven cam, and a pair of levers between which the cam is located, both of said levers having operative engagement with the hammer and both engaging with and being oscillated by said cam.
2. In a rock drill, a reciprocatable drill proper, a reciprocatable hammer coacting therewith, a reciprocatable counterbalance, 50 a lever pivoted intermediate its ends and operatively connected at one end with the hammer and at its other end with the counterbalance, and power operated means for oscillating said lever.
3. In a rock drill, a reciprocatable drill proper, a reciprocatable hammer coacting therewith, a reciprocatable counterbalance, a lever pivoted intermediate its ends and operatively connected at one end with the hammer and at its other end with the counterbalance and power operated means for oscillating said lever, and including a power operated stellate cam operatively engaging the lever to oscillate it.

4. In a rock drill, a reciprocatable drill proper, a reciprocatable hammer coacting therewith, a reciprocatable counterbalance disposed parallel to the hammer, springs acting to cushion the stroke of the counterbalance, a pair of levers each pivoted intermediate its ends and each operatively engaged at one end with a hammer and at its other end with a counterbalance, and power operated means for coincidentally oscillating said levers.

5. In a rock drill, a reciprocatable drill proper, a reciprocatable hammer coacting therewith, a reciprocatable counterbalance disposed parallel to the hammer, springs acting to cushion the stroke of the counterbalance, a pair of levers each pivoted intermediate its ends and each operatively engaged at one end with a hammer and at its other end with a counterbalance, and power operated means for coincidentally oscillating said levers including a stellate cam, the levers having protuberant and re-entrant portions with which the points of the cam engage.

6. In a rock drill, a reciprocatable drill proper, a reciprocatable hammer coacting therewith, a reciprocatable counterbalance disposed parallel to the hammer, springs acting to cushion the stroke of the counterbalance, a pair of levers each pivoted intermediate its ends and each operatively engaged at one end with a hammer and at its other end with a counterbalance, power operated means for coincidentally oscillating said levers including a stellate cam, the levers having protuberant and re-entrant portions with which the points of the cam engage, and means operated by one of said levers causing a step by step rotation of the drill in one direction.

7. In a rock drill, a casing, a drill mounted for rotation and reciprocation within the casing, a rotatable chuck mounted within the casing and within which the drill is reciprocatably disposed, a reciprocatable anvil mounted within the casing and normally bearing against the drill, a reciprocatable hammer disposed rearward of the anvil, cushioning means cushioning the rearward movement of the anvil and the rearward movement of the hammer, a reciprocatable counterbalance disposed within the casing parallel to the hammer, cushioning means adapted to bear against the opposite ends of the counterbalance at the ends of the stroke of the counterbalance, levers pivoted to the casing intermediate their ends and each of said levers at one end having engagement with the hammer and at its other end having engagement with the counterbalance, a power operated stellate cam disposed between the levers, the levers having protuberant and re-entrant portions with which

- the points of the cam are adapted to engage to thereby coincidentally oscillate the levers and reciprocate the hammer and counterbalance, and means operated by one of said levers for giving a step by step rotary movement in one direction to the drill chuck.
8. In a drill, a casing, a drill chuck mounted within the casing for rotation, a drill having a shank longitudinally reciprocatable within the chuck for rotation with the chuck, an anvil having a head disposed behind the chuck and the shank extending through the chuck and impacting against the shank of the drill, a hammer reciprocatably mounted within the casing behind the head of the anvil, means for cushioning the rearward movement of the anvil and the rearward movement of the hammer, a counterbalance reciprocatably mounted within the casing, resilient means disposed within the casing at opposite ends of the path of movement of the counterbalance, a pair of levers pivoted intermediate their ends, each lever at one end having rocking engagement with the hammer and at its other end having rocking engagement with the counterbalance, and power operated means disposed between the levers for coincidentally oscillating the levers.
9. In a drill, a casing, a drill chuck mounted within the casing for rotation, a drill having a shank longitudinally reciprocatable within the chuck for rotation with the chuck, an anvil having a head disposed behind the chuck and the shank extending through the chuck and impacting against the shank of the drill, a hammer reciprocatably mounted within the casing behind the head of the anvil, means for cushioning the rearward movement of the anvil and the rearward movement of the hammer, a counterbalance reciprocatably mounted within the casing, resilient means disposed within the casing at opposite ends of the path of movement of the counterbalance, a pair of levers pivoted intermediate their ends, each lever at one end having rocking engagement with the hammer and at its other end having rocking engagement with the counterbalance, power operated means disposed between the levers for coincidentally oscillating the levers and including a stellate cam, the levers having confronting protuberant and re-entrant portions with which the points of said cam engage.
10. In a drill, a casing, a drill proper, power operated means for reciprocating the drill including a power operated rotatable shaft, an exterior support upon which the casing is mounted for longitudinal movement and having teeth, an eccentric mounted on said shaft within the casing, an eccentric rod coacting therewith, a dog pivoted to the rod and projecting out through said casing and engaging said teeth, a stop preventing
- the dog from moving into angular relation to the rod in one direction but permitting the movement of the dog into angular relation to the rod in the other direction, and a spring resisting the last named angular movement of the rod.
11. In a drill, a casing, a drill proper, power operated means for reciprocating the drill including a power operated rotatable shaft, an exterior support upon which the casing is mounted for longitudinal movement and having teeth, an eccentric mounted on said shaft within the casing, an eccentric rod coacting therewith, a dog pivoted to the rod and projecting out through said casing and engaging said teeth, a stop preventing the dog from moving into angular relation to the rod in one direction but permitting the movement of the dog into angular relation to the rod in the other direction, a spring resisting the last named angular movement of the rod, a spring actuated dog projecting through the casing and engaging said teeth and holding the casing from reverse movement, and manually operating means for simultaneously lifting both dogs.
12. In a drill of the character described, a casing, a drill proper mounted within the casing, power operated means mounted within the casing for reciprocating the drill including a transverse power operated shaft, means for supporting the casing for longitudinal movement including a ratchet toothed rack, an eccentric mounted on the shaft, an eccentric rod coacting therewith and extending rearward and through the casing, a dog pivoted intermediate its ends upon the rod and engaging the teeth of said rack, a stop carried on the rod and limiting the movement of the dog to a position at an obtuse angle to the rod but permitting the dog to oscillate to carry the tail of the dog rearward and away from the said stop, and a spring normally holding the dog in engagement with the stop.
13. A drill of the character described comprising a casing, a rotatable chuck mounted within the casing, a reciprocatable drill proper mounted within the chuck and rotatable therewith, an anvil having a shank extending into the chuck and bearing against the drill, a reciprocatable hammer disposed behind said anvil, a pair of levers pivoted intermediate their ends, each lever having one end operatively engaging the hammer, a longitudinally extending counterweight parallel to the hammer with which the opposite end of each lever engages, cushioning springs receiving the impact of the hammer at opposite ends of its stroke, means for oscillating said levers comprising a shaft extending transversely of the casing and between the levers, a stellate wheel mounted upon the shaft for rotation therewith, the levers hav-

ing protuberant and re-entrant portions co-acting with the projections of said stellate wheel whereby the wheel shall cause the coincident oscillations of the levers in the same direction, a gear wheel mounted on the shaft, an idler gear wheel engaging the first named gear wheel and a driving gear wheel engaging the idler wheel and having a shaft extending to the exterior of the casing where-

by power may be applied to the train of 10 wheels, power operated means for rotating the drill chuck, and means for feeding the casing longitudinally toward the work.

In testimony whereof we hereunto affix our signatures.

JOSEPH M. NELSON.
TODD C. MORITZ.
WILLIAM DILLEY.
